US00D989103S

(12) **United States Design Patent** (10) Patent No.: **US D989,103 S**
Carrigan et al. (45) Date of Patent: **** Jun. 13, 2023**

(54) **DISPLAY SCREEN OR PORTION THEREOF WITH GRAPHICAL USER INTERFACE**

- (71) Applicant: **Apple Inc.**, Cupertino, CA (US)
- (72) Inventors: **Taylor Gerard Carrigan**, San Francisco, CA (US); **Patrick Lee Coffman**, San Francisco, CA (US); **Aled Williams**, San Francisco, CA (US)
- (73) Assignee: **Apple Inc.**, Cupertino, CA (US)
- (**) Term: **15 Years**
- (21) Appl. No.: **29/821,176**
- (22) Filed: **Dec. 28, 2021**

Related U.S. Application Data

- (63) Continuation of application No. 29/747,787, filed on Aug. 25, 2020, now Pat. No. Des. 940,182, which is a continuation of application No. 29/677,752, filed on Jan. 23, 2019, now Pat. No. Des. 897,371, which is a continuation of application No. 29/606,392, filed on Jun. 5, 2017, now Pat. No. Des. 843,405.

CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design. The dashed broken lines within the peripheral dashed broken line and the faded portions within broken lines illustrate portions of the graphical user interface that form no part of the claimed design.
